UNITED STATES PATENT OFFICE.

FRANK MANKOWSKY, OF CHICAGO, ILLINOIS.

FEED-WATER HEATER.

1,151,893.

Specification of Letters Patent. Patented Aug. 31, 1915.

Application filed December 9, 1914. Serial No. 876,338.

To all whom it may concern:

Be it known that I, FRANK MANKOWSKY, a citizen of the United States, residing at Chicago, in the county of Cook and State 5 of Illinois, have invented certain new and useful Improvements in Feed-Water Heaters, of which the following is a specification.

This invention relates to feed water heaters for steam boilers, and its object is to 10 provide a novel and improved feed water heater which utilizes the arch tubes in the fire box of the boiler, the heater being thus specially applicable to boilers of the locomotive type having a fire box in which is 15 mounted an arch supported on tubes connecting the front and rear water legs of the fire box.

In order that the invention may be better understood, reference is had to the accompanying drawing in which—

Figure 1 is a vertical longitudinal section through the fire box of the boiler showing the application of the invention, and Fig. 2 is a horizontal section on the line 2—2 of 25 Fig. 1.

Referring specifically to the drawing, 5 denotes the fire box of a boiler of the ordinary locomotive type. The fire box has the usual water legs and contains an arch 6 which is supported by tubes 7 connecting the front and rear walls of the fire box and opening into the water spaces. These arch tubes are employed for heating the feed water by mounting therein pipes 8 having 30 perforations 9 through which the feed water discharges into the tubes. The diameter of the pipes is less than that of the tubes, and they are therefore spaced from the interior surface of the latter. The pipes are connected at one end to the outside back sheet 10 of the fire box, and they are closed at this end by a plug 11. The other ends of the pipes pass through the outside front sheet 12 of the fire box, and are connected 40 thereto at a distributing box or chamber 13 mounted on the outside of the sheet 12 and extending transversely of the fire box, and made straight or curved to follow the contour of said sheet.

50 The water distributing chamber 13 has, on one side, midway between its ends, a laterally offset portion 14 to the opposite sides of which are connected the water supply pipes 15 leading from the injector or 55 feed pump. The chamber is divided into

a number of compartments by means of partitions 16, the number of such compartments corresponding to the number of pipes 8. Four of such pipes are shown, and the chamber is therefore provided with three partitions, forming four compartments, one for each pipe. The center partition extends straight from one side of the chamber, and the two end partitions extend convergently from said side. All three partitions also 60 extend partly into the offset portion 14 of the chamber.

In operation, the feed water enters the offset portion 14 of the chamber 13 and is divided by the partitions 16 so as to fill the 70 compartments at the same rate. The water in each compartment passes into the corresponding pipe 8 and is sprayed through the perforations 9 into the arch tubes 7. As the pipes are immersed in the hot water in the 75 arch tubes, the feed water is heated on its way to discharge into said tubes.

I claim:

1. The combination with a locomotive fire box having water legs and arch tubes connecting the same, of feed water pipes extending lengthwise through said tubes and discharging thereinto, and a distributing chamber mounted on the outside of the fire box and having a water inlet, said chamber 80 having partitions whereby it is divided into a plurality of compartments, to which the aforesaid pipes are connected respectively.

2. The combination with a locomotive fire box having water legs and arch tubes connecting the same, of feed water pipes extending lengthwise through said tubes and discharging thereinto, and a distributing chamber mounted on the outside of the fire box and having a water inlet, said chamber 90 having on one side an intermediate laterally offset portion to which the water inlet is connected, and partitions in the chamber dividing the same into a plurality of compartments to which the aforesaid pipes are 95 connected respectively, said partitions extending into the offset portion of the chamber.

In testimony whereof I affix my signature in presence of two witnesses.

FRANK MANKOWSKY.
